DESIGN FOR A DICTATING MACHINE

Charles W. Dann, Malden, Mass., and Gustav F. Braun, Elizabeth, and Richard M. Somers, West Orange, N. J., assignors to Thomas A. Edison, Incorporated, West Orange, N. J., a corporation of New Jersey

Application November 18, 1947, Serial No. 142,616

Term of patent 14 years

(Cl. D26—1)

To all whom it may concern:

Be it known that we, Charles W. Dann, a citizen of the United States and a resident of Malden, in the county of Suffolk and Commonwealth of Massachusetts, Gustav F. Braun, a citizen of the United States and a resident of Elizabeth, in the county of Union and State of New Jersey, and Richard M. Somers, a citizen of the United States and a resident of West Orange, in the county of Essex and State of New Jersey, have invented a new, original, and ornamental Design for Dictating Machine, of which the following is a specification, reference being had to the accompanying drawings, forming a part thereof.

Figure 1 is a perspective view of a dictating machine, embodying our novel design:

Figure 2 is a rear elevational view thereof; and

Figure 3 is a left-hand side elevational view thereof.

We claim:

The ornamental design for a dictating machine, substantially as shown.

CHARLES W. DANN.
GUSTAV F. BRAUN.
RICHARD M. SOMERS.
